UNITED STATES PATENT OFFICE.

WALTER J. BACHMANN, OF PHILADELPHIA, PENNSYLVANIA.

DESIGN FOR A GOGGLE-FRAME.

43,514.

Specification for Design.

Patented Feb. 11, 1913.

Application filed October 18, 1912. Serial No. 726,572. Term of patent 7 years.

To all whom it may concern:

Be it known that I, WALTER J. BACHMANN, a citizen of the United States, residing at the city of Philadelphia, in the county of Philadelphia and State of Pennsylvania, have invented a new, original, and ornamental Design for Goggle-Frames, of which the following is a specification, reference being had to the accompanying drawings, forming part hereof, in which—

Figure 1, is a front elevation, showing the shape or configuration of the lens-frames of the article of my new design; and Fig. 2, is a top or plan view, showing the peculiar rear bowing of said lens-frames and which

in conjunction with the frontal formation of the said lens-frames, as shown in Fig. 1, define thereby main features of my said design invention.

I claim:—

The ornamental design for a goggle-frame, as shown and described.

In witness whereof, I have hereunto set my signature in the presence of the two subscribing witnesses hereto.

WALTER J. BACHMANN.

Witnesses:

THOMAS M. SMITH,
HELEN F. MILLER.
